US00D888049S

(12) **United States Design Patent** (10) Patent No.: **US D888,049 S**
(45) Date of Patent: **** Jun. 23, 2020**

(54) **ELECTRONIC DEVICE**

- (71) Applicant: **Apple Inc.**, Cupertino, CA (US)
- (72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Daniele De Iuliis**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Joe Sung-Ho Tan**, San Francisco, CA (US); **Clement Tissandier**, San Francisco, CA (US); **Eugene Antony Whang**, San Francisco, CA (US); **Rico Zörkendörefer**, San Francisco, CA (US)

- (73) Assignee: **Apple Inc.**, Cupertino, CA (US)

- (**) Term: **15 Years**

- (21) Appl. No.: **29/625,109**

- (22) Filed: **Nov. 7, 2017**

Related U.S. Application Data

- (63) Continuation of application No. 29/579,214, filed on Sep. 28, 2016, now Pat. No. Des. 806,701, which is

a continuation of application No. 29/574,078, filed on Aug. 11, 2016, now Pat. No. Des. 803,825.
